UNITED STATES PATENT OFFICE.

CHARLES JOHNS, OF PITTSBURG, AND WILLIAM D. EYNON, OF PHILADELPHIA, PENNSYLVANIA.

METHOD OF FORMING PILES.

No. 837,933.

Specification of Letters Patent.

Patented Dec. 11, 1906.

Application filed May 2, 1905. Serial No. 258,543.

To all whom it may concern:

Be it known that we, CHARLES JOHNS, a resident of Pittsburg, in the county of Allegheny, and WILLIAM D. EYNON, a resident of Philadelphia, in the county of Philadelphia, State of Pennsylvania, have invented a new and useful Improvement in Methods of Forming Piles; and we do hereby declare the following to be a full, clear, and exact description thereof.

Our invention relates to a method of utilizing old railroad-rails in the manufacture of metallic piling.

Heretofore in the manufacture of metal piling it has been customary to roll the piles from ingots or billets to the proper length with an enlargement or head and a seat or recess, so that when several are joined together the head of one pile fits in the recess of the adjoining pile to form an interlocking joint, so as to form a continuous structure of this character which is practically watertight. The rolling of such a pile from an ingot or billet, however, is a very expensive operation, due to the peculiar shape of the pile in cross-section, while at the same time the several heats necessary to reduce it to the proper shape reduces the strength and rigidity of the steel.

The object of our invention is to provide a metal piling which can be made at greatly-reduced cost and at the same time one which will be stronger and more durable.

To these ends our invention comprises, generally stated, the method of utilizing old and defective rails for the manufacture of piles, which consists in heating such rails and subjecting the same to a succession of rolling-passes, providing in the rolling-passes space for lateral expansion and for reduction of the head on the side nearest the web, it being thus made possible both to increase the width of the web and reduce the size of the head, so as to provide interlocking means through the reformation of the base, so that a number of the piles produced may be connected together, as above set forth.

To enable others to practice our invention, we will describe the same with reference to the accompanying drawings, in which—

Figure 1 represents a set of rolls suitable for reducing the rails to piling. Fig. 2 is a perspective view of the rail before rolling to pile form. Fig. 3 is a view of the finished

pile. Fig. 4 shows a number connected together.

Like numerals indicate like parts in each.

In carrying out our method of forming piles we may employ any suitable apparatus, that illustrated comprising the rolls 2, 3, 5, journaled in the housings 4. Horizontal rolls 5 are also supported by the housings 4, and the rolls 2, 3, and 5 may be driven by any suitable power. Three passes 6, 7, and 8 are illustrated, although it is of course apparent that more may be employed, if necessary.

In the practice of our invention we take an ordinary railroad-rail 9, either one that has been in use or a "second" or defective rail, and after the same has been heated to the proper degree it is put successively through the passes 6, 7, and 8 of the rolls. (Shown in Fig. 1.) These roll-passes are of such shape as to provide for the lateral expansion of the rail by rolling part of the head into the web and the reduction of the head on the side nearest the web, so providing for the widening of the web portion in the finished pile. As shown in the drawings, in all these passes the width of the pass for the web portion is increased successively, thus providing space for the rolling of the head into the web and the lateral expansion of the blank. In its passage through the pass 6 the horizontal roll 5 will also act to reduce the size of the head 10 of the rail, while the rolls 2 and 3 will act to force the head toward the said roll 5, also acting on the flanges to bend them downwardly and form a rudimentary groove or recess. In the passage of the blank through the pass 7 space is provided for the still further widening of the web portion and the further reduction of the head and increasing the depth of the recess. The rail is then passed through the pass 8, which reduces the thickness of the web and further widens the same and gives to the rail substantially the shape shown in Fig. 3, having the web 12, the recess or groove 11, and the head 13. It is apparent that by the reducing of the head of the rail and by the form of the passes a portion of the head is rolled into the web to increase its width, while at the same time the flanges are bent over to form a groove or recess 11, so completing the pile.

By starting with an old rail not only is the

first cost very small, since these can be bought as scrap-iron, but as the shape of the rail approximates in a general way the finished shape of the pile the labor and cost of shaping the pile are very greatly reduced over that necessary when starting with a billet or bloom. One peculiarity of our invention is that in this rolling of the reheated rail it is subjected to a succession of rolling-passes, and that in these rolling-passes space is provided for lateral expansion and at the same time for the reduction of the head on the side nearest the web, so that the metal of the head is rolled into the web, and the web is thus widened in such way as to provide the necessary width of web in the finished pile from the narrower web of the rail, and at the same time the head is so reduced in size that it can be brought to proper shape for interlocking with the recess 11 of the finished pile, which is formed from the base-flange portion of the rail. Such widening of the web portion by the reduction of the metal of the head and the forcing of the same into the web is we believe entirely new in the art and a new conception in rolling. Furthermore, the reduction to the finished shape can be done at one heat, so that the strength and rigidity of the metal are not lessened or destroyed. Old rails, furthermore, have the advantage of containing a very high percentage of carbon—much higher than billets or blooms. Since the metal is stiffer, the webs can be rolled thinner without sacrificing the necessary stiffness of the piling, and the width of the web can therefore be increased.

The piles when finished are connected up in the ordinary manner by having the head of one fit into the groove in the adjacent one, so as to form a continuous and practically watertight joint.

The shape of the groove or head may vary, if desired, and it is furthermore apparent that the recess may be formed in the head of the rail instead of by the flanges, as illustrated.

By making use of old rails or seconds we get the benefit of the high quality of steel employed and are able to purchase the same at a low cost as compared to the cost of new material.

What we claim is—

1. The method of utilizing old and defective rails for the manufacture of piles, which consists in heating the rail and then subjecting the same to a succession of rolling-passes and providing in the rolling-passes space for lateral expansion and for the reduction of the head on the side nearest the web, and thereby providing for rolling the metal of the web into the head and widening the same.

2. The method of utilizing old and defective rails for the manufacture of piles, which consists in heating the rail and then subjecting the same to a succession of rolling-passes and providing in the rolling-passes space for lateral expansion and for the reduction of the head on the side nearest the web, and thereby providing for rolling the metal of the head into the web and widening the same while holding the base-flange portion of substantially the same section.

3. The method of utilizing old and defective rails for the manufacture of piles, which consists in heating the rail and then subjecting the same to a succession of rolling-passes and providing in the rolling-passes space for lateral expansion and for the reduction of the head on the side nearest the web, and thereby providing for rolling the metal of the head into the web and widening the same, and at the same time bending the base-flanges downwardly and inwardly to form a locking-recess.

In testimony whereof we, the said CHARLES JOHNS and WILLIAM D. EYNON, have hereunto set our hands.

CHARLES JOHNS.
WILLIAM D. EYNON.
